UNITED STATES PATENT OFFICE.

GEORGE PIERCE, OF MONTREAL, QUEBEC, CANADA.

HEADLIGHT-DIPPING MECHANISM.

Application filed May 29, 1925. Serial No. 33,779.

The invention relates to head light dipping mechanism, as described in the present specification and illustrated in the accompanying drawings that form part of the same.

The invention consists essentially of the novel features of construction pointed out broadly and specifically in the claims for novelty following a description containing 10 an explanation in detail of an acceptable form of the invention.

The objects of the invention are to afford comfort and safety to motorists in travelling by night, whereby the glare can readily 15 be eliminated without affecting the usefulness of the lights; to firmly support the lamps notwithstanding their change in position and thus effect rigidity in the construction at all times; to insure low costs of 20 construction and thereby bring profit to the manufacturers, as well as bring this device within the reach of all motor car owners, in order that the use may become general and by this means avoid many of the deplorable 25 accidents resulting from confusion due to the blinding glare; and to provide a reliable and efficient mechanism economical in regard to production and maintenance and easy to operate.

30 In the drawings, Figure 1 is a side elevation of the mechanism.

Figure 2 is a fragmentary side elevation of the cam plate and spindle.

Figure 3 is a detail of the cam plate.

35 Figure 4 is an enlarged detail of a locking bolt.

Figure 5 is a sectional detail of Figure 4.

Figure 6 is an elevation of the inner locking ring and annular channel.

40 Figure 7 is a detail of the open end of the inner surface in lamp mounting locking ring.

Figure 8 is a sectional detail of the inner locking ring.

Figure 9 is a detail showing the closed end 45 of the inner locking ring.

Figure 10 is a sectional detail through the spindle operating gear.

Figure 11 is a detail of the outer locking ring and return spring.

50 Figure 12 is a detail of the housing for the locking mechanism.

Figure 13 is a side elevation of the mechanism complete as applied to a vehicle.

55 Figure 14 is an enlarged assembled view of the locking mechanism.

Figure 15 is an enlarged sectional view of the locking mechanism.

Fig. 16 is a detail of the bearing rod joint.

Like numerals of reference indicate corresponding parts in the various figures.

Referring to the drawings, the tube 20 forms an aligning bearing for the tube 21, the latter being a rotatable mounting for the lamps and the former being rigidly supported in the bracket 22, which are secured 60 to the frame of the vehicle, through the mud guards.

The lamp mounting 21 carries the customary brackets 23, to which the lamps 24 are 70 rigidly secured.

The flanged ring 25 is formed with the annular flanges 26 and encircles the lamp mounting 21 adjacent to the lamp bracket 23 and forms an annular channel surface 27 between said flanges, said ring and mounting 75 being slotted at 28, said slot 28 having radial end walls registering with a longer slot 29 in the tubular aligning bearing 20.

The pin 30 having the forked end 31 to 80 form the pivot bearing 32, is inserted through the slots 28 and 29 and is screwed into the spindle 33 extending into the tubular aligning bearing 20 at one end and forming part of the locking mechanism.

The pivot bearing 32 is secured to the connecting rod 34 and this connecting rod 34 is pivotally secured to the toggle joint 35, one of the toggles of said joint forming part of the operating lever 36, and another extending loosely into the lower end of the 90 dash bracket 37 at the upper end of which said lever 36 is pivoted.

The spring 38 encircles the lower toggle between the bracket 37 and the joint end of 95 said toggle, and this spring maintains the connecting rod 34 in tension and in compression as the case may be.

The spindle 33 of the locking mechanism carries the cam plate 39 which is secured to said spindle by the lug 40 from said plate, 100 projecting through the slot 41 in tubular self aligning bearing 20 and bushing 42.

The cam plate 39 is formed with the cam slots 43, 44 and 45, the slot 44 having rising 105 surface both ways from the centre and corresponding to the intermediate position of the head lights, and the slot 43 having its rising surface towards the extreme end and corresponding to the upright position of the head lights and the slot 45 having an ex- 110

tended rising surface from one end and corresponding to the low position of the head lights.

The cam plate 39 is contained within the locking ring 46, and this ring 46 is secured on the hub 47 which is sweated on the rotatable lamp mounting 21, or secured by a clamp.

The twin lugs 48 extend from the side wall of the ring 46 and form a bearing for a return spring 49. The spring ball 50 projects outwardly from the wall diametrically opposite twin lugs 48 and operates as explained hereinafter.

The locking bolts 51, 52 and 53 operate respectively in the bolt holes 54, 55 and 56, through the ring 46. These holes and bolts represent the high, intermediate, and low position of the lamps.

The bolts 51, 52 and 53, are each slotted at 57 to form a fork to engage the cam plate over the slots 43, 44 and 45, and the screws 58 secure said locking bolts in said slots and these form the bearings on the rising surface of the cam slots to return the bolts to their inner position after being shot into their locking positions.

The outer locking ring 59 is rigidly secured to the bracket 22 and is formed with the bolt holes 60, 61 and 62, for the high, intermediate and low positions respectively, of the head lights, and within said ring return spring 49 having curled ends engages the twin lugs 63, thereby forming a strong hold as said spring is brought into tension at the lowering of the head lights.

The bevelled lug 64 projects from the wall of the locking ring 59 inwardly outside of the spring 49 in the path of the spring ball 50, so that when said light is in the upper position said spring ball is in spring contact with this lug on the flat surface thereof, and to move the head lights to the intermediate position this spring ball slides off the lug which then forms a stop surface and together with the lever spring 38 rotates the cam plate 39 into position to shoot the bolt 52 into the bolt hole 61 of the outer locking ring and thereby form a rigid locking connection between the locking ring 46 rigid with the tubular bearing and rotatable mounting of the head lights and the rigid bracket 22 bolted to the frame of the vehicle.

The housing 65 encloses the outer locking ring 59 and is held thereto by the screws 66. The housing 65 is formed with the arc slot 67 which forms a limiting slot in the turning of the inner locking ring 46, as the screw 68 is inserted to stop the inner locking ring 46 and projects through said slot.

The cushion spring 69 is introduced into the channel surface 27 against the stop 70, the latter being formed of a headless screw

screwed into the bed of the channel the pin 30 operating against the pressure of the spring 69 to bring the pin back to a definite position.

The cover 71 closes in the channel surface 27 and this cover moves with the pin 30 which maintains the said cover in place as a dust protector at the same time the brake shoe 72 is secured to said cover, and rubs the channel surface 27 merely as a retarding member and it is quite possible that in many cases this retarding shoe will not be required.

In the operation of this device the parts are assembled as described, so as to form an enclosed casing in the line of shafting carrying the lamps, this casing being dust tight, and occupying but little space and therefore in no way damaging the appearance of the motor vehicle.

The two locking rings, that is to say, the inner locking ring, securely and very rigidly mounted on the tubular rotating member carrying the lamps and the outer locking ring rigidly secured to the aligning bearing and bracket, form together a chamber as the inner ring telescopes into the outer ring, both of these rings extending from end walls, and this chamber, that is to say the rings are flanged inwardly to their mountings, thus completely closing in the said chamber.

The inner ring as explained in the description of the details rotates and the outer ring has the housing permanently secured thereto, and remains stationary therewith, therefore so far as the eye is concerned there is a complete stationary casing, in which the inner ring turns for a part of a revolution.

The lever 36 and its connecting rod to the crank pin, extending through the slots in the flanged ring, the tubular lamp mounting and the tubular aligning bearing is indissolubly connected with the operation of the inner locking ring as it entirely depends on the position of this lever for the shooting of the bolts and this is particularly noticeable in selecting the intermediate position, that is to say, six degrees off the vertical.

It will be noticed that the slots in the flanged ring and the lamp mounting extend inwardly in a radial direction from either end to the slot in the tubular self aligning bearing, but the latter is the longer slot, in order that the crank pin may engage the radial wall at either of the mounting slot to move said mounting one way or the other as the case may be, for the said longer slot provides the pathway for the pin's movements.

The mounting slot is of sufficient length to permit the operation of the locking mechanism, in fact it is somewhat overlength, in order to accommodate the particular movements in connection with the actuation of

the parts of the said mechanism. Therefore the cushion spring in said flanged ring is introduced to maintain the said crank pin substantially in mid position in the said 5 mounting slot.

The control in the dipping of the lamps is naturally entirely from the lever pivotally mounted on the dash bracket of the car, and this lever is connected through its toggle 10 mechanism with the connecting rod to the crank pin and except in its mid position the said connection is in tension or compression according to the positions of the lamp. Therefore presuming the lamp to be in its 15 vertical position and locked to the bolt in the outer locking ring, the first movement of the lever before the crank pin comes to the end of the lamp mounting slot turns the cam plate, and this draws the bolt from its 20 engagement in the outer locking ring by the contact of the bolt pin with the rising surface in the cam slot.

Coincidently with the drawing of this bolt, the bolt pin of the intermediate bolt 25 moves to a high surface in its particular cam slot, so that it cannot shoot to place immediately when its particular hole in the outer locking ring comes in register therewith. Thus the continued movement of the 30 lever will carry the locking mechanism without interruption on to the low position and as the bolt locking pin of the low position bolt has already been in high position, in its cam slot, the continued movement to the 35 limit moves said pin to low position in its cam slot with the result that as soon as the low position bolt reaches its hole in the outer locking ring it shoots thereinto.

The return movement is precisely the 40 same for the slot in the tubular mounting provides the necessary play for the crank pin to rotate the cam plate first before the rotation of the mounting begins. Therefore previous to any movement of the tubular members the bolt pin rises in the cam slot and withdraws the low position bolt to permit the rotation of the lamp mounting and coincidentally pass the bolt pin of the intermediate bolt on to the rise of the intermediate 45 cam slot on the opposite side thereby holding the intermediate bolt to its withdrawn position while passing the intermediate bolt hole in the outer ring.

The six degree dip from the vertical is 50 however the one that is likely to be the most used and consequently it is essential that it should be done in a positive and simple manner with perfect security that the bolt will be shot on every occasion. Therefore on the 55 movement of the lever for the second position, the spring ball which has been in engagement with the flat surface of the bevelled lug moves off said lug and abuts the bevelled surface thereof at the far edge.

Meanwhile the connecting rod to the oper-

ating lever is still in tension, therefore the tendency is to pull back on the crank pin which has been moved forward and this reverses the rotation of the cam plate from the position it has reached in its forward 70 movement and thus brings the cam slot into a mid position in relation to the bolt pin of the intermediate bolt. This mid position is the low position, consequently the bolt shoots into its hole in the outer locking ring 75 as there is nothing whatsoever to maintain it in its withdrawn position.

The double rise in the intermediate cam slot provides for the withdrawal of the intermediate bolt from either direction, so that 80 the lamps can be moved from high to low therefrom.

In the return movement from low to intermediate the bolt can be shot in exactly the same way, as the spring ball then engages 85 the same bevel and the connecting rod is in a state of tension, in fact every movement is quite the same and the main object is reached by bringing the bolt pin of the intermediate bolt in mid position in its cam slot. 90

The through operation and the way operation have now been fully described and it will be seen that all the contingencies have been provided for, and nothing is left to the judgment of the driver for the lock mechanism at the touch of the lever rights itself 95 to the several positions and once the bolt has been shot the rigidity of the lamps is just the same as if mounted on a rod permanently secured to the brackets and frame. 100

The spring ball may be adjusted so far as the pressure in the bevelled flat lug is concerned by regulating the compression of the spring therebehind.

Another feature of this invention is the 105 means employed for facilitating the installation of the device and this is done at the opposite end of the self aligning bearing 20, which there terminates in a ball 73. The supporting bracket 74 secured to the vehicle 110 frame is in this case a plate 75 with a ball projection 76. The clamping plates 77 and 78 formed as double ball sockets 79 and 80 have the mid plate portions 81 and 82 through which the bolt 83 extends to be 115 fastened, by the nut 84 suitably locked, therefore by inserting the ball 76 in the socket 80 and the ball 73 in the socket 79 and tightening the plates together by the bolt 83 drawn by the nut 84, the joint is 120 made and after the proper adjustment is secured, it can be finished as rigidly as the lamps themselves on their own mounting.

It is obvious that the ball 73 may be made 125 the means of adjusting the length of the self aligning tube by having a stem to it, this stem being finally secured by rivets at the lock end of the self aligning bearing.

It has been mentioned that the outer locking ring 59 is closed in at its outer edge by 130

an inwardly extending flange to the tube 20, this inwardly extending flange indicated by the numeral 85, joins a hub 86, which encircles the end of the self aligning bearing tube 20 and is encircled by the clamp 87 forming part of the bracket 22.

The clamp 87 securely holds the tube 20 through the bushing 42, the latter extending through said hub 86 within the clamp 87, so that the three parts, namely the clamp 87, the hub 86, and the bushing 42 may be permanently and rigidly secured together by the pin 88, as it is not required that these parts should be removed for any cause other than the taking down of the whole machine.

What I claim is:—

1. In a headlight dipping mechanism, a tubular lamp mounting having a cross slot, bearing brackets adapted to be secured to the vehicle frame, a tube having a cross slot and rigidly secured to said brackets and forming a bearing member for said mounting, a crank shaft inserted in said bearing member and having its crank member projecting through said slots, a lock mechanism secured to said mounting and said bearing member respectively and fixedly securing them in three selective positions in relation to one another, and an operating lever mechanism for selecting a first, second or third position and secured to said crank member.

2. In headlight dipping mechanism, a stationary tubular bearing having a transverse slot, a lamp mounting in tubular form and mounted on said bearing and having a shorter transverse slot, a rotary member in said bearing having a crank pin therefrom projecting through said slots, a lever operatively connected to said crank pin and a lock mechanism having a spring bolt radially sliding in a lock part secured to said lamp mounting, a bolt hole member secured to the bearing support and a cam member rotated independently of said rotating lock part to withdraw the bolt previous to the shooting of a bolt.

3. In headlight dipping mechanism, tubular lamp mounting and bearing members transversely slotted, a lock mechanism having inner and outer casings forming a lock chamber containing a cam plate with cam slots and spring bolts secured to said cam plate by pins extending through bolt lugs and through said cam slots, a rotary spindle within said bearing member having a lug secured thereto and to said cam plate and a crank pin therefrom extending through the transverse slots of said tubular members and a lever operatively connected to said crank pin.

4. In headlight dipping mechanism, a locking mechanism formed of inner and outer casings connected by a return spring and containing a bolt carrying member hav-

ing cam slots and rotatable independently of the inner lock casing and radially operating spring bolts carried thereby, means for rotating said bolt carrier and said outer casing following the initial operation of the bolt carrier, and means for creating a pause in the rotation preceding the shooting of one of said bolts.

5. In headlight dipping mechanism, a locking mechanism having inner and outer casings adapted to lock the lights to upright intermediate and low positions and connected by a return spring and having a spring ball in one part meeting a bevelled lug in the other in rotation forming a pause and aligner for the shooting of the intermediate bolt and a lever operatively connected with the bolt carrier of said lock mechanism and with the rotatable inner casing and acting under spring influence continuously in co-action with the aforesaid bevelled lug and spring ball.

6. In headlight dipping mechanism, a locking mechanism having a rotating inner casing and sliding bolts mounted therein for high, intermediate and low lamp positions, an outer casing having high, intermediate and low bolt holes suitably spaced, a bolt carrier within said inner casing having cam slots shaped to withdraw the bolts, spring pressing outwardly on said bolts, a return spring connecting said casings, a crank mechanism operating said bolt carrier and said inner casing, a lever constantly under spring influence and connected to said crank mechanism, a lamp mounting carrying the said inner casing and slotted for the crank and a bearing containing the crank rotor and slotted for the crank pin.

7. In headlight dipping mechanism, a bearing bracket, an outer casing having a hub clamped and pinned to said bracket and encircling a tubular bearing, a lamp mounting rotating on said tubular bearing, an inner casing clamped to said lamp mounting, a shell enclosing said outer and inner casings and rigidly secured to the former, and having a limiting slot, a return spring connecting said outer and inner casings, a pin from said inner casing extending through said limiting slot, a bolt operating spindle in said tubular bearing having a crank pin extending therethrough and through said lamp mounting, a bolt carrier fixedly mounted on said spindle and operated by said crank pin and having spring bolts secured thereto through cam slots and sliding through said inner casing into said outer casing and a lever operatively connected with said crank pin.

8. In headlight dipping mechanism, bearing brackets adapted to be secured to the frame of the vehicle, one of said brackets having a ball joint member, tubular mem-

bers forming a lamp mounting and a bearing member, a ball joint member projecting from one end of the latter, turn ball joint casings engaging said balls and fixedly secured, a locking mechanism at the other end of said bearing member and clamped to the other bracket and having a rotating

part secured to said lamp mounting, and means for operating said locking mechanism.

Signed at Montreal, Canada, this 14th day of May, 1925.

GEORGE PIERCE.
